UNITED STATES PATENT OFFICE.

EDWARD C. ROBERTS, OF SALTVILLE, VIRGINIA.

CARBURETER.

1,289,914.

Specification of Letters Patent. Patented Dec. 31, 1918.

Application filed July 9, 1917. Serial No. 179,604.

To all whom it may concern:

Be it known that I, EDWARD C. ROBERTS, a citizen of the United States, and a resident of Saltville, in the county of Smyth and State of Virginia, have invented a certain new and useful Improvement in Carbureters, of which the following is a specification.

The present invention relates to carbureters and more particularly to a device for carbureting air with heavy hydrocarbons, such as kerosene, and the like, for use in internal combustion engines, and an object of the invention is to provide a device of this character, comprising a capillary feed for the fuel and a plurality of baffle disks for directing air in a sinuous path through the capillary feed for the hydro-carbon to effectively carburate the air to form a combustible mixture.

The above, and various other more or less important objects and advantages of this invention will be in part described, and in part understood, from the following detailed description of the present preferred embodiment, the same being illustrated in the accompanying drawings wherein:

Figure 1 is a view in elevation of a hydro-carbon vaporizer constructed according to the present invention,

Fig. 2 is a detail enlarged section taken longitudinally through the air heater.

Fig. 3 is a transverse section taken on the plane indicated by the line 3—3 in Fig. 2.

Fig. 4 is a detail enlarged elevation, partly in section of the main body portion of the vaporizer.

Fig. 5 is a transverse section taken through the air and fuel mixer at one side of the apparatus on the plane indicated by line 5—5 in Fig. 4.

Fig. 6 is a fragmentary side elevation of the air-distributing tube in said mixer.

Referring to these drawings, A and B designate two tanks or sources of supply adapted to contain hydro-carbon fuels of different specific gravities, such as: gasoline and kerosene respectively.

The tanks or containers A and B are connected by pipes 10 and 11 to the opposite ends of the distributing chamber or tank 12 which is shown in the present instance as in the form of a drum having closure flaps 13 on opposite ends to which the pipes 10 and 11 are connected. The drum 12 is provided between its ends, and preferably to-

ward one end thereof, with a partition 14 dividing the drum 12 into two compartments adapted to respectively receive the hydro-carbon fuels of different specific gravities. Preferably, the partition 14 is located adjacent to the end of the drum 12 into which the pipe 10 opens to provide a relatively small compartment for the gasoline, or the higher grade of fuel.

An air feeding pipe 15 extends upwardly and diametrically through the opposite ends of the drum 12 at the opposite sides of the partition 14. The pipes 15 are connected, by T-couplings 16, or the like, to an air pipe 17 which leads from an air drum or casing 18 provided in its underside and at one end, with an air inlet opening 19. The pipe 17 opens into the opposite end, and at the top side of the drum 18 to receive air therefrom after the air has passed longitudinally and upwardly through the casing or drum 18. A heating coil 20 is disposed within the drum or casing 18 and is connected to an exhaust pipe 21 which preferably leads from the exhaust of an internal combustion engine. The coil 20 receives the heated exhaust gases from the pipe 21 and is adapted to raise the temperature of air passing through the casing 18, and to deliver the heated air to the air pipe 17.

Arranged about each pipe 15 is a liquid feeding wick 22 which, as shown in Figs. 4 and 5, is of cylindrical formation and entirely surrounds the pipe 15. The wick 22 extends upwardly through the drum 12 to a considerable extent about the pipe 15, and the drum 12 is provided with a tubular projection or casing 23 surrounding the wick 22 and tapering at its upper end to engage the wick, and to seal the casing 23 about the upper portion of the pipe 15. The pipe 15 is provided, at its portions which extend through the casing 23, with a plurality of relatively large perforations or openings 24 whereby the suction of air upwardly through the pipe 15 will draw the liquid absorbed by the wick into the pipe 15. The pipe 15, above the casing 23, is imperforate, and the pipes 15 are connected at their upper ends, by means of T-couplings 25 or the like, to a common manifold or supply pipe 26 which may be connected directly to the intake manifold of an internal combustion engine. The pipe 15 which extends through the smaller compartment of the drum 12 may be provided at its upper end with a con-

trolling valve 27 by means of which the gasoline, or the higher grade hydro-carbon fuel, may be cut off from the manifold pipe 26. The pipe 26 is provided, between the nozzles 15, with a controlling valve 28 to regulate the flow of the vaporized heavier hydro-carbon from the larger compartment of the drum 12.

Each pipe 15 is provided, within the mixing portion thereof, with a plurality of baffle disks, 29 which may be mounted upon a rod 30 extending longitudinally through each pipe 15 and being headed or otherwise secured at its opposite ends in the adjacent 15 T-couplings 16 and 25. The baffle disks 29 are preferably located opposite the openings 24 in the pipes 15 and are adapted to deflect the air passing upwardly through the pipes into the openings 24 to restrict 20 the passage through the pipes 15 at such points and thus increase the suction created by the air passing upwardly through the tube. The wicks 22 extend down into the drums 12 adjacent to the bottom thereof 25 so as to expose a considerable length of each wick to the fluid contained in the drum. It is of course understood that the drum 12 may be in the form of a tank of suitable size to carry the desired quantity of fuel, 30 and that the tanks A and B may be eliminated.

In use, if it is desired to start an engine by the use of the higher grade hydro-carbons, it is only necessary to close the valve 35 28 and open the valve 27. The suction of the engine is transmitted to the pipe 26 and the latter draws air upwardly through the pipe 15 from the pipe 17 and the drum or casing 18. The air thus drawn upwardly 40 through the pipe 15 is deflected by the baffle plates 29 and creates an increased suction at the openings 24. The fuel within the small compartment of the drum 12 is absorbed by the wicks 22 and carried upwardly into the casing 23. This absorbed fuel is drawn inwardly through the openings 24 and carried into the manifold 26 with the air which passes upwardly through the pipe 15.

50 As soon as the engine is started, the exhaust gases therefrom heat the coil 20 and the interior of the drum 18. The air passing through the drum 18 is thus raised to a relatively high temperature, and increases 55 the vaporization of the fuel fed to the mixer, generally designated at 23. If it is now desired to operate the engine on a less volatile hydro-carbon, such as kerosene, the valve 27 may be gradually closed and the valve 28

gradually opened. After the valves have 60 been respectively closed and opened, the air is drawn upwardly through the pipe 15 which projects the larger compartment of the drum 12. The same mixing action takes place in the mixer 23 which communicates 65 with the larger compartment, the vaporized hydro-carbon being carried with the heated air into the manifold 26 and past the valve 28 to the engine.

It is of course understood that the valves 70 27 and 28 may both be partly opened in order to admix the fuels and thus obtain the maximum efficiency of the engine under certain conditions which may be found in the use of the same, and for the purpose 75 of economizing in the consumption of the fuel.

It is of course understood that various changes and modifications may be made in the details of construction and design of 80 the above specifically described parts to adapt the device for application to motor vehicles, motor boats and other places met with during the use and installation of the device, without departing from the spirit 85 of this invention; such changes and modifications being restricted only by the scope of the following claims.

I claim:—

1. In a carbureter, the combination of a 90 drum, a casing rising from one end of the drum, a wick arranged in said casing and extending into the drum, an air pipe projecting upwardly through the drum, and through the casing, said air pipe having 95 apertures in its sides in the portion passing through said casing, and a plurality of baffle disks within said air pipe for directing the air in a sinuous path through the pipe.

2. In a carbureter, the combination, of a 100 drum, an air pipe projecting upwardly through the drum and having perforations intermediate its end, a casing communicating with and projecting from the drum and surrounding said air pipe, a wick arranged 105 in said casing and projecting into the drum to absorb fuel and feed the same into said casing, a feed pipe connected to said air pipe for drawing air upwardly therethrough for contact with the wick to admix the fuel with 110 air, and a plurality of horizontal baffle disks positioned in said air pipe in alignment with the adjacent perforations of the pipe, said disks being smaller in diameter than the bore of the air pipe to direct the 115 air in a sinuous path through the air pipe.

EDWARD C. ROBERTS.
